UNITED STATES PATENT OFFICE.

JONATHAN T. BROWN, OF MARBLEHEAD, MASSACHUSETTS, ASSIGNOR,
BY MESNE ASSIGNMENTS, TO UNITED LAST COMPANY, OF BOSTON,
MASSACHUSETTS, A CORPORATION OF MAINE.

ART OF FORMING LAST PARTS.

SPECIFICATION forming part of Letters Patent No. 783,363, dated February 21, 1905.

Application filed May 28, 1900. Serial No. 18,261.

To all whom it may concern:

Be it known that I, JONATHAN T. BROWN, of Marblehead, in the county of Essex and State of Massachusetts, have invented a new and useful Improvement in the Art of Forming Last Parts, of which the following is a specification.

Prior to my invention it has been the practice in the manufacture of hinged lasts to first turn from a block of wood the entire last and then cut it transversely into two sections. These sections were then recessed at the top to permit the heel-section to move upward and provide abutting members below the pivotal point of the last, the sections being bonded by a hinge. A last is of such irregular form that it has been found in practice prior to my invention exceedingly difficult and expensive to properly align and bond the two sections after they have been separated as above described. In turning the whole last from which the hinged lasts were made prior to my invention it has been the practice to "chuck" the stock lengthwise of the grain without regard to any relationship between the axis of rotation and any particular face or line of the finished last.

In following my invention I separately turn and produce complemental last-sections, each fore part being turned to align with and accurately fit a standard heel part.

In carrying out my invention I form each section with a predetermined face before putting it into the lathe, so that either section can be secured to the chuck, hereinafter described, with its predetermined face against the face of the chuck. The same chuck is used for turning the fore parts and the heel parts and may be said to represent the face of the heel part when the fore part is being turned and the face of the fore part when the heel part is being turned. The predetermined face is formed at one end of the block. The fore-part sections and heel-sections, faced as aforesaid, are turned independently from separate blocks or pieces of stock upon a specially-organized machine hereinafter described, by which and by means of the predetermined face

of the block and the chuck each section can be turned with its axis or its axis of rotation when 50 in the chuck bearing a predetermined relation to the said predetermined face of the section. The predetermined face of the heel-section bears a predetermined relation to the said predetermined face of the fore-part section, 55 and the longitudinal axis of one section bears a predetermined relation to the longitudinal axis of the complemental section, so that the axis of the completed last is the same as if the last had been turned solid and never divided. These 60 relations of axes and faces are maintained throughout the making and assembling of the sections or parts of the last. The fore parts and heel parts turned as described when assembled accurately fit in a predetermined way with their 65 faces and surfaces in proper position and alignment, their abutting ends being a predetermined residue of their respective predetermined faces in relation to which they were turned and assembled. It is not essential that 70 the predetermined face referred to should subsequently be retained as a whole in the section, as the inner end of the section, together with a portion of the face, may be afterward beveled or shaped in accordance with the variety of last being manufactured. This face or its equivalent, however, during the process of manufacture is essential and serves as a gage in relation to which the various dimensions, shapes, and alinements of lasts are made. 75 In addition to the predetermined face I form in the said face near the center two holes which engage pins on the chuck. These holes are preferably bored at right angles to the predetermined face and not only serve as 80 means by which the block is turned, but in connection with the flat face serve as means by which the block is accurately adjusted against the chuck and in the templets employed in the operation subsequent to turning, 85 the said templets preferably having, like the chuck, a flat face with two pins projecting at right angles to said face to enter said holes. Instead of the pin and holes I may employ 90 any other suitable means for the described purpose. Further, the principle of employ- 95

ing the flat face may be variously modified. For convenience and certainty of results I prefer the face above described and the hole-and-pin construction.

5 It will be evident from the foregoing that when a fore part is being turned the chuck stands in relation of the heel-section for that fore part, and vice versa, so that when a fore part and heel part have been turned and finished necessarily their complementary surfaces and faces are accurate in fit and alinement.

In manufacturing sectional lasts prior to my invention it has been customary, as heretofore described, to turn the last precisely the same as solid lasts and thereafter cut up the lasts. In making the solid lasts or in making sectional lasts the last is turned with its axis running from the toe to a point substantially near the central part of the heel portion. In cases where there was but little spring the axis running from the toe to the central part of the heel above referred to would pass through the lower part of the rear face of the fore part instead of the central part. If the last being turned was the same size as the model, this position of the axis would develop no particular difficulty. It is impracticable, however, to have a model for each size, the practice being to have one model for each style of last and then by the reproducing method of the last-turning machine to make lasts of all sizes of the same style as and from that particular model in order to have a complete set of sizes of a last of that style.

35 In turning a solid last that is larger or smaller than the model (and the hinged lasts made prior to my invention have been nothing but solid lasts subsequently cut up) while the lathe could be adjusted to correctly multiply the length of the last-model as desired it did not and failed to correctly reproduce on an increased or diminished scale, as the case might be, the desired measurements of the model about the body of the last, particularly on lines running about the instep and the heel measure. Instead of correctly reproducing the desired measurements at these points the last, if it were of a larger size than the model, would have its measurements unduly increased at these points, and if of a smaller size than the model the measurements at these points would be too small, the increase or diminution of measurements becoming more marked in proportion as the last being turned was greater or less in size than the model. Many expedients were adopted to overcome this difficulty, but with only indifferent success, as the resulting last when larger or smaller than the model still had improper measurements about the fore part, due to the axis of the last being off center of the fore part and the consequent multiple action of the machine in reproducing the model on a larger or smaller scale.

Owing to the irregular contour of lasts, it is desirable, for many reasons, among which

may be mentioned making lasts of a larger or smaller size than the model, to turn the last about an axis which extends in a line from the center of the toe backward and upward to substantially the center of the material at the end 70 engaged by the chuck. By this means when sections of a larger or smaller size than the model are turned there is no excessive exaggeration or diminution of the dimensions of the model, as would be the case if the axis at 75 the chuck were near one surface of the block or materially off center. This result I obtain by turning the fore part and the heel part separately by means of the described chuck-and-pin construction and the face and central 80 holes in the block, thereby having the material of the last evenly distributed about its axis of rotation while in the lathe, the chuck practically constituting the complementary heel part, and vice versa. The axis of the last is 85 also correctly maintained and the axis and surfaces of one part correctly alining with and form a continuation of those of the other part or section. In a word, by my invention I produce a hinged last in which the measurements, 90 surfaces, and alinements are correctly maintained irrespective of the grade or size above or below the model.

Referring to the drawings, Figure 1 represents a portion of a turning-lathe, the pattern-wheel and the cutter being shown in dotted lines. Fig. 2 represents the chuck, the chuck-carrier, and the last-section held in place by the chuck-carrier. Fig. 3 represents a plan view of the chuck-carrier. Figs. 4 and 5 represent the 100 adjustable coupling for the shaft which drives the chuck-carriers, by means of which the patterns and the stock may be rotated in exactly the same relation to the pattern-wheel and the cutter. Fig. 6 represents a longitudinal section through the chuck. Fig. 7 represents a longitudinal section through the same on the line 7 7 of Fig. 6. Fig. 8 represents a section on the line 8 8 of Fig. 6. Figs. 9, 10, 11, 12, and 13 represent the chuck in 110 detail. Fig. 14 represents the partially-finished fore part, the last-block or rough stock being shown in dotted lines. Fig. 15 represents the end of the finished fore part. Fig. 16 represents the gage-plate which is clamped 115 against the end of the section. Fig. 17 represents in full lines a fore-part block. Fig. 18 represents the fore part as finished by the lathe. Fig. 19 represents a heel-block. Fig. 20 represents a heel part as finished by the 120 lathe. Fig. 21 represents a heel part and a fore part as finished by the lathe, showing the relation of the complementary faces with the hole-and-pin construction, the pins appearing at c'.

Referring to the drawings, which illustrate one embodiment of the invention, 20 represents the usual swinging frame which carries the pattern and the stock to be turned, said frame being oscillatory with relation to the 130

pattern-wheel 21 and the cutter 22, which are mounted and rotated in the usual manner. The frame is provided with the end bars 23 24 and the intermediate cross-bars 25 26 27. 5 In the bars 23 and 26 is journaled a split shaft 28 29, the sections of which are connected by a coupling, which I shall subsequently describe. Said shaft is provided with the usual pulley 30, driven by a belt 31, and on the shaft 10 are pinions 32 33, intermeshing, respectively, with gears 34 35 on the chuck-carrying shafts 36 37. The shaft 36 is journaled in bearings in the end bars 33 and the cross-bars 25, the shaft 37 being journaled in the cross-bars 26 15 27. On the frame are two adjustable cross-bars 38 and 39, the latter being adjusted by a screw-bar 40 and being held in place after adjustment by a set-screw 41. These cross-bars 38 and 39 carry the studs or spindles 42 20 43, which hold the pattern and the stock against their respective chucks and permit their rotation, said spindles having their axes coinciding with the axes of the shafts 36 and 37.

As thus far described the machine does not 25 differ in any essential point from the well-known turning-lathe now in general use, except in the mechanism by means of which the shafts 36 37 may be rotatively adjusted with relation to each other, as will be subsequently 30 explained.

On each of the shafts 36 37 is a universally-adjustable chuck, and as the two chucks are similar I shall describe only one of them, reference being now had to Figs. 2 to 13, inclusive. The end of the chuck-carrying shaft 35 is formed with a round head, which is transversely grooved in the face thereof to provide two flanges 43 43, the inner faces of which are parallel, as shown in Fig. 9, and the two 40 flanges are likewise grooved inward from the edges to provide curved lips 44 45. The lips 45 are apertured at 46 46. Between the flanges 43 is pivoted a lug 47 by means of a screw-pin 48. This lug 47 projects rearwardly from a 45 coupling consisting of a plate 481 having forwardly-projecting flanges 49 49, whose inner faces are at a right angle to the inner faces of the flanges 43. The lug 47 is bevelled from its center toward its edges, as shown 50 in Fig. 7, to permit it to be swung about the screw-pin 48. 50 indicates the chuck proper, which is pivoted between the flanges 49 49 by a screw-pin 51, so that said chuck has a universal adjustment with relation to the axis 55 of the shaft. Adjusting-screws 52 52 are passed through the coupling 481 to bear against the rear edges of the chuck 50 to adjust the latter, said screws being secured after adjustment by nuts 53 and the coupling 481, 60 together with the chuck, adjusted in a direction at right angles to the chuck adjustment and secured after adjustment by the screws 54 54 and nuts 55 55, said screws being passed through the coupling 481 and the lug 47 and 65 bearing against the inner wall of the groove

formed transversely in the head at the end of the shaft. The front face 56 of the chuck is preferably flat, and two pins 57 57 project forwardly therefrom, as shown. (See Fig. 11.) Against the face 56 a gage-plate 58 is 7c replaced, said plate having apertures 59 to receive the pins 57. Inasmuch as each of the chucks may be universally adjusted with relation to its shaft, it will be seen that the stock and the pattern may be gripped by the 75 spindle against the chuck in exactly the same position with regard to each other and the axis of rotation. In order to rotatively adjust the pattern and the stock relatively to each other, the coupling shown in Figs. 2 to 80 5 is employed for connecting the two sections 28 29 of the shaft previously referred to. Said coupling consists of two confronting collars 60 and 61, rigidly secured to the meeting edges or ends of the shaft 28 29. Screws 85 62 62 are passed through curved slots 63 from the collar 61 into the collar 60. Thus it will be seen that one of said shafts may be rotatively adjusted and timed with relation to the other, after which the two may be rigidly 90 secured by driving the screw 62 home, so as to bind the collars firmly together to prevent them from slipping. This adjustment enables the stock to be rotated in true relation to the rotation of the pattern and when once made 95 does not require further attention, since this factor is a constant irrespective of the varying sizes or styles or shapes of the model. This accurate adjustment has not been necessary in lathes employed for making hinged 100 lasts prior to my invention, since all sizes or styles of lasts were turned to the same fixed axis and blocks for all kinds of lasts were chucked alike. By my invention, on the contrary, the blocks are differently chucked with 105 relation of the face of the chuck to the axis of rotation, and the axis of the last is determined before the block is chucked. The sections being turned with relation to a predetermined face or gage, it is necessary that the 110 block and pattern should rotate in true unison. While such unison of rotation is theoretically possible, in a machine as a practical proposition some adjusting means are necessary to secure this mode of operation, owing 115 to imperfection of parts, &c. In accordance with my invention, therefore, the pattern-dog and block-dog are both adjusted alike, not only with respect to the pitch of the face of each dog to the line running from the point 120 of the spindle to the center of the dog-face, but also by means of the adjustment between the driving mechanisms of the dogs and each and every point, and the last or block held by the block-dog is necessarily in true adjustment to the corresponding point upon the model. These adjustments, together with the particular way in which the stock is held to distribute the material of the finished section 125 substantially equal about the axis, enables me 130

to accurately reproduce the sections of different sizes of the model.

The process by means of which the last-sections are constructed and which includes the operation of the machine above described is as follows: The end of the larger portion of the last-block *a* is faced, as at *b*, and in the said end are bored, by means of a suitable tool, two parallel apertures *c c* in substantially the central part of the face, said face *b* and the apertures *c* corresponding to a similar face and similar apertures on the pattern *d*. The pattern *d* is then placed upon the pattern-chuck, and the chuck is adjusted until the end of the last is engaged at the proper point by the spindle 42, a slight indentation or hole being made in the said end for this purpose. The pattern is then placed upon the stock-chuck with the face of the pattern flat against the plate 58 on the chuck 50. The stock-chuck is adjusted until the pattern is in position to receive the point of the spindle in the aforesaid indentation, after which the adjusting devices are locked to hold the chuck continuously in that position so long as that particular style of fore part or heel part is being manufactured or turned. The pattern is then replaced in the pattern-chuck and the spindle is engaged in the indentation described. The last block or stock is placed upon its proper chuck with the pins 57 57 entering the apertures *c c*, and the face *b* is forced firmly against the face of the plate 58, it being remembered that there is also a plate 58 on the pattern-chuck. Then the cross-bars 39 are adjusted to bring the spindle 43 into engagement with the end of the stock. The machine is set in operation and the stock is turned to form a fore part or heel part exactly similar to the pattern, and it will be noted that each time this is done the axis of rotation of the stock bears a predetermined relation to the flat face at the end of the stock. I do not mean by this that the axis on which each fore part is turned always bears in different styles of fore parts the same relation to the flat face, for it will be readily seen that right lasts and left lasts are turned on axes which are at different angles to the flat faces and that differently-shaped fore parts are turned on axes which vary in their relation to the flat face; but it will be noted, however, that if fifty or any other number of fore parts of a certain style or shape for a right shoe or a left shoe of a certain size be turned they will all be rotated on axes bearing the same predetermined relation to the flat face, said face serving as a gage for the operation. I have illustrated a fore part in the machine; but it will be understood that the heel part is constructed in exactly the same way, said heel-section being provided with a flat face which is apertured to receive the pins carried by the chuck, as shown in Figs. 19 and 20. It is further to be noted that the stock-chuck represents a com-

plemental heel-section while a fore-part section is being turned. After the sections have been turned the squared ends thereof may be beveled or otherwise shaped, this and all subsequent operations being accomplished by placing the said flat faces and their holes in engagement with templets that are duplicates, so far as their faces and holding members are concerned, of the face and pieces of the stock-chuck, thereby maintaining to the end the relationship of the various faces and alinements of the sections and insuring the accurate and proper fitting and alinement of the two sections when assembled. In Figs. 18 and 20 I have shown the fore part and heel-section as being beveled on the line *e*. In making hinged lasts the lower portion of the face *b* is left on both the heel-section and the toe-section, since said faces confront each other below the axis of the pindle and meet when they are in normal or operative position. After the sections have been turned the subsequent steps will depend upon the particular style of last, style of hinge, &c. A description of the subsequent steps is unnecessary beyond the instructions that when the sections are being worked upon to secure surfaces, alinements, fittings, &c., they are held by the described templet, thus, in effect, having the fore part held by its complementary heel part, and vice versa. The holes in the sections may be utilized to position and anchor the hinge.

I do not claim the mechanism for practicing my improved art, said mechanism being shown, described, and claimed in a divisional application, Serial No. 62,051, filed May 27, 1901.

Having thus explained the nature of my invention and described a way of constructing and using the same, though without attempting to set forth all of the forms in which it may be made or all the modes of its use, what I claim, and desire to secure by Letters Patent, is—

1. As an improvement in the art of forming lasts or last parts, the method which consists in forming a surface other than the foot-shape contour of the last or last part, such surface having a definite geometric relation to a surface having a useful function in the last, and then forming the said contour in a predetermined relation to such first-mentioned surface substantially as and for the purpose described.

2. As an improvement in the art of forming divided lasts, the method which consists in forming a standard surface on each of several last parts, which surfaces bear a definite relation to each other, forming the foot-shape contours of such last parts in proper relation to such standard surfaces, and then assembling the parts substantially as and for the purpose described.

3. The method of making sectional lasts consisting in turning from separate pieces of stock a toe-section and a heel-section, each section being turned on an axis bearing a pre-

determined relation to a mounting-face thereof first formed thereon, and the axis of one section being a continuation of the axis of the complementary section.

5 4. The herein-described method of making a divided last consisting of severing the last-block before it is turned, finishing the secant end thereof to the ultimate shape of the joint

end of the last part and then subsequently turning the block.

In testimony whereof I have affixed my signature in presence of two witnesses.

JONATHAN T. BROWN.
